CLAIM

The ornamental design for a scooter interface device, as shown and described.

DESCRIPTION

FIG. 1 is a front perspective view of a hardware module including our design;

FIG. 2 is a rear perspective view thereof;

FIG. 3 is a front-facing view thereof;

FIG. 4 is a back-facing view thereof;

FIG. 5 is a left-facing view thereof; and,

FIG. 6 is a right-facing view thereof.

The broken lines for the purpose of illustrating portions of the scooter interface that form no part of the claimed design. The dot-dash broken lines shown in the drawings depict boundaries of the claim and form no part of the claimed design. The broken lines and adjacent unshaded surface in FIGS. 1-3 are included to identify parts of the article's appearance that form no part of the claimed design.
